UNITED STATES PATENT OFFICE.

JOHN J. ROACH, OF BUTTE, MONTANA.

LANTERN.

SPECIFICATION forming part of Letters Patent No. 595,209, dated December 7, 1897.

Application filed March 30, 1897. Serial No. 630,006. (No model.)

To all whom it may concern:

Be it known that I, JOHN J. ROACH, a citizen of the United States, residing at Butte city, in the county of Silver Bow and State 5 of Montana, have invented certain new and useful Improvements in Lanterns; and I do hereby declare the following to be a full, clear, and exact description of the invention, such as will enable others skilled in the art to 10 to which it appertains to make and use the same.

My invention relates to improvements in lanterns, and has for its object to provide a cheap device of comparatively little weight which may be conveniently carried by means 15 of a simple attachment upon an ordinary dinner-pail, such as is used by miners and other workmen.

My invention consists of the novel devices hereinafter described and claimed.

Reference is had to the accompanying drawings, wherein the same parts are indicated by the same letters throughout the several views.

Figure 1 represents a front view of my lantern attachment as carried upon a dinner-pail. Fig. 2 is a view of the lantern and dinner-pail shown in Fig. 1, as seen from the right in said figure; and Fig. 3 is an enlarged central vertical section taken on the line 3 3 20 in Fig. 1.

A represents the lantern attachment, and B represents the pail or bucket upon which the said lantern is carried.

The front A' of the lantern is open and is 25 fitted with a sheet of glass, isinglass, or other transparent material which fits in the vertical slideways a' a' and rests at its bottom in the horizontal slideway a⁰. This sheet is adapted to be lifted vertically for any reason— 30 such, for instance, as to light the lantern.

The sides of the lantern are provided at their rear edges with vertical longitudinal flanges a² and a³, respectively. Upon one of these vertical flanges, such as a², a wire C, bent at its upper end to form a hook c and bent outward and downward at its lower end to form the stud c', is soldered or otherwise attached along its middle portion c² to the said flange a². This hook c and stud c' are 35 adapted to engage in small vertical sockets or sleeves b and b', respectively, secured to

the side of the pail B, as seen most clearly in Fig. 1. These hooks and sleeves form a hinge-joint which allows the body of the lantern to swing to or from the body of the pail. 55 Upon the other flange a³ are formed two small vertical sleeves a⁴ and a⁵ a short distance apart, and a similar sleeve b² is secured to the side of the pail in a position to fit in between the two sleeves a⁴ and a⁵, with its central opening in line with the central openings of both of said sleeves. A pin or key D, composed of a piece of wire having a straight body d and a bent top d', is adapted to pass through said sleeves when in line, and to thus 60 secure the swinging end or side of the lantern to the body of the pail, as seen in Figs. 1 and 2.

The top and bottom of the lantern are each made concave at the inner edge to conform 70 to the curve of the body of the pail. The top is provided with a suitable chimney or smoke-outlet E, which is soldered to said top and which is surmounted by a hood or cap F. This hood or cap is attached to the chimney by means of a plurality of small vertical strips e, soldered or riveted to the parts.

In the center of the bottom of the lantern is formed a circular socket A², adapted to receive a piece of candle when desired. An 80 oil-reservoir I, having a socket or chamber I' in its under side, fits over the candle-socket A² and rests upon the bottom of the interior of the lantern-body, as seen in Fig. 3.

The oil-reservoir or lamp-body A² is provided with an opening in its top, into which is fitted a hollow screw-plug H, provided with suitable tubes h for one or more wicks, or any other suitable form of burner may be used.

The lantern-body has no back, as seen in 90 Fig. 3; but when in position upon a pail, as shown, the side of the pail forms the back wall of the lantern and also acts as a reflector, as will be obvious. In this way the lantern can be made much lighter in weight and 95 much less expensive than if a back provided with a reflector was provided.

It will be obvious that my lantern attachment may be attached to any ordinary dinner-pail after its first having been provided 100 with the three small sleeves b, b', and b², as herein described.

It will also be seen that either a candle or oil may be used in the lantern, the oil-reservoir or lamp-body I being removable at will.

The pail is provided with a suitable bail or handle B' for carrying the same.

Having thus described my invention, what I claim, and desire to secure by Letters Patent of the United States, is—

1. The combination with the pail B having 10 the sleeves or sockets b and b' and the sleeve b² secured to the sides thereof; of a lantern having an open front provided with a transparency therein, and being entirely open at the back; vertical side flanges at the back 15 thereof; a wire soldered along one of said flanges and bent at its upper end to form a hook, and at its lower end to form a stud adapted to engage said sleeves b and b'; a pair of sleeves secured to the other of said 20 flanges a short distance apart; and a wire rod or key adapted to pass through said pair of sleeves and through said sleeve b² on the pail, and thus hold the lantern firmly thereon, substantially as described.
- 25 2. The combination with the pail B having the sleeves or sockets b and b', and the sleeve

b² secured to the sides thereof; of the lantern A having open front provided with a transparency therein, and being entirely open at the back; vertical side flanges a² and a³ at 30 the back thereof; hooks upon one of said flanges adapted to engage in said sleeves or sockets b and b' and form a hinge-joint; a pair of sleeves upon the other flange a short distance apart, and a wire rod or key adapted to 35 pass through said pair of sleeves and through said sleeve b² on the pail, and thus lock the lantern-body thereto; a candle-socket mounted upon the floor of said lantern, and an oil-reservoir having a socket or chamber in its 40 under side adapted to fit over said candle-socket, resting in the lower part of the said lantern, and provided with a suitable burner, substantially as and for the purposes described.

In testimony whereof I affix my signature in presence of two witnesses.

JOHN J. ROACH.
